UNITED STATES PATENT OFFICE

VANCE ROBERT MAYNARD, OF GREENSBORO, NORTH CAROLINA, ASSIGNOR TO THE STAFFORD COMPANY, OF READVILLE, MASSACHUSETTS, A CORPORATION OF MASSACHUSETTS

HARNESS CONNECTER FOR LOOMS

Application filed October 7, 1930. Serial No. 486,956.

The present invention has relation to harness connecters, and in particular to such devices as are designed to attach the harness cords to the frames of the harnesses. It has 5 as its object to provide novel and improved means for attaching the harness cords to the frames of the harnesses or heddles with capacity for quick and easy detachment and reattachment of the cords to permit removal 10 and replacement of the harnesses, and also with capacity for simple, easy, and minutely accurate adjustment of the effective length of the cords to remove all slack and keep the rigging in tight relation assuring accuracy in 15 the actuation of the harnesses in their shedding action.

To these ends, the invention comprises a portion adapted to be engaged with the end 20 of the cord or other harness-supporting and actuating device, and with a screw-head, button or similar headed projection on the harness frame, the nature of the connection between this portion and the headed projection 25 being such that disconnection and reconnection can be easily effected by a relative lateral movement of the two parts. To prevent accidental separation, the parts are preferably combined so that disconnection will require first a relative movement of the said portion 30 of the connecter toward the frame and axially of the projection, and second, a lateral movement of this portion at substantially right angles to the first direction of movement. The unhooking movement thus compelled to have components of motion in two 35 directions at right angles to each other is further restricted through confining the lateral movement to a single plane extending along the axis of the headed projection, so that while the connecter is designed when in use to rotate about the axis of the headed projection, there are only two points in each revolution at which the aforesaid axial and lateral movements will enable the parts to be 40 disconnected. In this manner a method of attaching and detaching the parts is provided which, while easily effected by the simplest of manual operations, is practically impossible to accomplish accidentally in the 45 course of the working of the loom. The in-

vention further comprises the combination with the novel attaching and detaching provisions of the well-known turnbuckle means of adjusting the effective length of the harness cords to attain the desired or correct 55 tension.

An illustrative embodiment of the invention is shown in the drawings, in which,

Fig. 1 shows a portion of a loom, indicating a harness frame and cord therefor attached to the frame through the use of the invention. 60

Fig. 2 is a fragmentary view on a larger scale of a portion of the connecter in engagement with the headed projection fixed on the harness frame. 65

Fig. 3 is a view similar to Fig. 2 showing the said portion of the connecter in process of being disengaged from such projection on the frame. 70

Fig. 4 is a view of the projection and Fig. 5 a detail of the portion of the connecter designed to engage with the projection on the harness frame. 75

At 1 is indicated the arch of a loom having the usual sheaves 3 from which pass the cords 5 which work the harnesses 7 up and down in usual manner to form the shed. At 9 is indicated the frame of the harness, usually of wood, which is provided with projections 10 extending upwardly from its upper edge, 80 (and similarly downwardly from its lower edge,) characterized by an enlarged portion or head and a shank having a thin or reduced part between the head and the surface of the frame. Herein this projection is constituted by a screw driven into the wood of the frame so that a half inch or so of its shank 11 is exposed adjacent the head 13. The portion 15 of the connecter which engages with the head of the screw is in the form of a loop of 85 metal having an axial bore 17 through its closed lower end fitting easily the diameter of the shank 11 of the headed projection or screw. A lateral slot 21 is cut in one sidewall of the loop 15 communicating radially with the bore 17, and a portion of the shank 11 is slabbed off at both sides in parallel planes as is indicated at 19 to produce a flattened portion of the shank capable of being 90 passed easily through the lateral slot 21 to 100

bring the shank of the screw into position within the bore 17. Other non-circular shaping of such reduced portion of the shank than that shown may be adapted if desired, the aim being to attain a shape in section such as will limit the passage of the reduced part through the slot 21 to movement in a single plane having fixed angular location with respect to the axis of the projection 10. 5 Preferably, though not necessarily, the head of the projection or screw fixed in the frame is chamfered at its under surface 23,—a construction well-known in wood screws to enable them to be countersunk,—and the seat 10 15 adjacent the upper end of the bore 17 is similarly countersunk, so that when the loop 15 is drawn away from the frame the head will seat itself accurately concentric with the bore 17.

20 Preferably also, the slabbed-off portion 19 of the shank 11 terminates a distance below the head substantially equal to the depth of the material through which the bore is formed, so that when the head is seated in the upper end of such bore 17 the portion of the shank then standing within the bore 17 will be of complete circular section. This arrangement makes it impossible for the screw to escape from its engagement with 25 the loop through relative lateral movement unaccompanied by axial movement, for the portion 27, of the full diameter of the shank, which separates the head 13 from the reduced part at 19 is too thick to pass through 30 the slot 21.

35 The arrangement of the reduced part of the shank of non-circular section, as produced by slabbing-off the portions 19 or otherwise, prevents escape of the head 13 of the screw or other projection from the loop 15 when the harness frame arrives at the end of its travel and the momentum or overthrow of the frame tends momentarily to lift the head 13 off of its seat. In use, after the connection between 40 the head and the loop 15 has been established by inserting the reduced part at 10 between the sides of the slot 21, the loop 15 is given a quarter turn so as to bring the longest dimension of the non-circular or slabbed-off 45 reduced part out of line with the slot 21. In the working of the loom there is little or no tendency for relative axial rotation to occur between the loop 15 and the headed projection 10, as a result of vibration or other 50 causes, and the relative angular position given to the two portions is satisfactorily maintained. In this relation, even a pronounced slackness in the cords 5 or other harness supporting and actuating means with resultant decided overthrow tending to produce axial movement between the headed projection 10 and the loop 15 will not result in the escape of the head from its seat in the loop 15.

55 To provide for the necessary adjustment

of the effective length of the harness cords or devices 5 in convenient and accurate manner, the loop 15 is combined with a member 29, the upper end of which is screwed into or otherwise secured to the extremity of the cord 5 according to any well-known or desired manner, while the lower end is threaded throughout a liberal portion of its length and screwed into a threaded hole formed axially in the upper end of the loop 15, as in the familiar turn-buckle. By virtue of the novel form of engagement contrived between the headed projection 10 and the loop 15, which permits free axial rotation of one of such members with respect to the other while they are in engagement, the obvious advantages of easy, accurate and extensive adjustment of the tension of the cords resulting from the screw-threaded extensibility of the connector are obtained. 70 75 80 85

It will be noted by reference to Figs. 2 and 3 that the space between the sides of the loop is increased slightly at the lower end as indicated at 31 at and adjacent the seat 25, so as to admit freely the head 13 which is of greater diameter than the width of the space above such extended portion 31. This arrangement operates as indicated in Fig. 3 to terminate the relative axial movement of the screw and the loop by bringing the sides of the head into contact with the side walls of the loop 15, when the reduced or slabbed-off part of the shank 11 is opposite the slot 21 in the seat. This makes it easier and simpler for the attendant to detach the connector, as the parts 90 95 100 are automatically arrested with the reduced or slabbed-off portion of the shank exactly in line with the slot, and to complete the disengagement he has only to exert a light lateral force on the loop 15 in the proper direction while rotating the latter through a quarter turn or so, and is saved from having to determine accurately the amount of axial movement which he must give to the parts. 105 110

What I claim is,—

1. In a loom, a harness connector having, in combination, a portion in connection with the harness frame and a portion in connection with the harness supporting and actuating devices, the two portions being adapted for relative rotation about a common axis during engagement and adapted to be disengaged through relative axial and lateral movement. 115

2. In a loom, a harness connector having, in combination, a portion in connection with the harness frame and a portion in connection with the harness supporting and actuating devices, one thereof having a head and the other a seat receiving such head upon relative movement of the two portions transversely to the direction of strain exerted through the connector when in use. 120 125

3. In a loom, a harness connector having, in combination, a portion in connection with

the harness frame and a portion in connection with the harness supporting and actuating devices, one thereof having a head and the other a seat to engage the surface of the head adjacent its shank, the seat having a slot through which the shank may pass laterally into axial relation with the seat.

5. In a loom, a harness connector having, in combination, a portion in connection with the harness frame and a portion in connection with the harness supporting and actuating devices, one thereof having a head and the other a seat to engage the head, the seat having a slot whereby the two portions may be engaged and disengaged through relative lateral movement.

6. In a loom, a harness connector having, in combination, a portion in connection with the harness frame and a portion in connection with the harness supporting and actuating devices, one of such portions having a head and the other a slot adapted to hook over the head.

7. In a loom, a harness connector having, in combination, a portion in connection with the harness frame and a portion in connection with the harness supporting and actuating devices, one of such portions having a head and the other a slot adapted to hook over the head, and to permit relative rotation of the two portions while thus hooked together.

8. In a loom, a harness connector having, in combination, a portion in connection with the harness frame and a portion in connection with the harness supporting and actuating devices, one of such portions having a head and the other a slot adapted to hook over the head, and means for varying the effective length of the harness supporting and actuating devices.

9. In a loom, a harness connector having, in combination, a portion in connection with the harness frame and a portion in connection with the harness supporting and actuating devices, one of such portions having a head and the other a slot adapted to hook over the head, the slotted portion being adjustably combined with the harness supporting and actuating devices to vary the effective length of the latter.

10. In a loom, a harness connector having, in combination, a portion in connection with the harness frame and a portion in connection with the harness supporting and actuating devices, one of such portions having a head and the other a slot adapted to hook over the head, the slotted portion being in screw-threaded connection with the harness supporting and actuating devices to vary the effective length of the latter.

11. In a loom, a harness connector having, in combination, a portion in connection with the harness frame and a portion in screw-threaded extensible connection with the harness supporting and actuating devices, the

two portions being adapted for relative rotation during engagement and adapted to be disengaged through relative lateral movement.

12. In a loom, a harness connector having, in combination, a portion in connection with the harness frame and a portion in connection with the harness supporting and actuating devices, one of such portions having a head and a shank adjacent thereto which has a thin place in its length, and the other portion having a slot one part of which is substantially equal in width to the thickness of the thin place in the shank and another part of which is of the full width of the shank.

13. In a loom, a harness connector having, in combination, a portion in connection with the harness frame and a portion in connection with the harness supporting and actuating devices, one of such portions having a head and a shank a part of which latter is of non-circular section, and the other portion having a seat and a lateral slot leading to said seat, adapted to permit passage of the non-circular part of the shank only when the narrowest dimension of such part is disposed transversely of the slot.

14. In a loom, a harness connector having, in combination, a portion in connection with the harness frame and a portion in connection with the harness supporting and actuating devices, one of such portions having a head and a shank reduced in thickness in a part of its length, and the other portion having a seat for the head, an aperture for the shank in such seat, and a slot communicating with the aperture admitting the reduced part only of the shank.

15. In a loom, a harness connector having, in combination, a portion in connection with the harness frame and a portion in connection with the harness supporting and actuating devices, one of such portions having a head and the other portion having a seat engaged by the head to prevent separation of the two portions.

16. In a loom, a harness connector having, in combination, a portion in connection with the harness frame and a portion in connection with the harness supporting and actuating devices, one of such portions having a head and a shank having a part of reduced thickness which is separated from the head by a length of the shank which is of full diameter, and the other portion having a seat and a lateral slot leading to such seat, adapted to permit passage of the reduced portion only of the shank.

17. In a loom, a harness connector having, in combination, a portion in connection with the harness frame and a portion in connection with the harness supporting and actuating devices, one of such portions having a head and a shank having a part of non-circular section, and the other portion having a

- seat including an aperture of the full width of the shank, and a slot communicating with the aperture adapted to permit passage of the non-circular section therethrough when the longest dimension of such section is aligned with the passage.
17. In a loom, a harness connector having, in combination, a portion in connection with the harness frame and a portion in connection with the harness supporting and actuating devices, one of such portions having a head and a shank with an intermediate part of reduced thickness, and the other portion having a seat and a lateral slot permitting passage of the reduced part of the shank to and from the seat, and means limiting relative axial movement of the two portions when the reduced part has been brought in line with the seat.
18. In a loom, harness supporting and actuating devices having, in combination, a harness-cord, a member attached to the end of such cord, a second member in screw-threaded extensible connection with the first member and having a slotted seat, and a headed member in connection with the harness adapted to be engaged with such slotted seat and disengaged therefrom by relative lateral movement, and adapted to permit relative rotation of the second member about a common axis to effect the said screw-threaded extensibility while engaged with the slotted seat.
19. In a loom, a harness connector having, in combination, a portion in connection with the harness supporting and actuating devices and a portion in connection with the harness, one of such portions having a head and the other being adapted to hook over such head and thereafter to rotate freely about the axis of such head, with the relative axial and lateral movements which are incident to such hooking and unhooking action restricted to a single plane with respect to each of such portions.
